UNITED STATES PATENT OFFICE.

HENRY A. FINK, OF OAK PARK, ILLINOIS, ASSIGNOR TO CONTINENTAL CAN COMPANY, INC., OF NEW YORK, N. Y., A CORPORATION OF NEW YORK.

PACKING DEVICE FOR FILLED-CAN-CLOSING MACHINES.

Application filed November 5, 1926. Serial No. 146,444.

The invention relates to new and useful improvements in packing devices for filled can closing machines, and more particularly to a packing device which operates to depress the floating content of the can.

An object of the invention is to provide a device of the above character with means whereby any floating content which overlies the flanged edge of the can body may be cut off, so as to permit the floating content to be forced down into the can body without leaving any content in engagement with the flange.

A further object of the invention is to provide a device of the above character, wherein the pad or head which moves down into the can body for depressing the floating content thereof, is provided with a recess and perforations or openings leading therefrom to the face of the pad or head, whereby the liquid content of the can body may pass up into the recess and subsequently drain back into the can when the pad or head is removed therefrom.

These and other objects will in part be obvious and will in part be hereinafter more fully described.

In the drawings which show by way of illustration one embodiment of the invention—

Figure 1 is a view partly in front elevation and partly in section showing a portion of a closing machine having the improvements applied thereto;

Fig. 2 is an enlarged sectional view through the packing head, also showing the can body which is being entered by the packing head, and

Fig. 3 is a lower front view of a portion of the packing head.

The invention is directed to a packing device for a filled can closing machine, which is so constructed as to depress the floating content of the can prior to the passing of the can body into the closing machine. It has been found in practice, that often some of the floating content, particularly in connection with string beans, is likely to overlie the flange on the can body, and when the packing head comes down to depress the floating content, this overlying portion is clamped against the flange and is not depressed. The overlying portion of the content will then go into the closing machine overlying the flange, and when the cover is

placed, this content works into the double seam and causes a leak. The present invention is directed particularly to the construction of the packing head, whereby means is provided for severing the overlying portion of the content, so that the content remaining in the can may be depressed into the can body. This is accomplished by placing on the packing head, a cutter, which surrounds the packing head, and is spaced therefrom so as to move down over the flange of the can body and thus sever any content lying on the flange and extending beyond the same. This packing head is also provided with a recess or chamber and with perforations leading from the lower face of the pad or head on the packing device into said recess or chamber. This permits the liquid content of the can to pass up into said recess or chamber without overflowing the can, which is quite an advantage, particularly in the putting up of string beans or similar food products. Of course, when the head is lifted from the can body, the liquid content or brine will drain back into the can.

Referring more in detail to the drawings, I have shown the invention as applied to a closing machine consisting of a main supporting frame 1 carrying a bracket in which is mounted a rotating drum 2. At 3 is indicated the support for the can body, and the can body when placed on this support, is raised into proper position for the double seaming of the end on to the body by a double seaming mechanism. A cover feeding mechanism is located above this support 3. In the drawings, the can body is indicated at C. It is about to be moved on to the drum, and the thread 4 will engage behind the can body and move the same along a suitable supporting rail and guide bar to the support 3. These features are all of well-known construction, and it is not thought necessary to define the closing machine more in detail. Attached to this main frame 1 is a bracket 5, and mounted on the bracket 5 is a packing pad 6. The packing pad 6 is carried by a supporting shaft 7, which not only rotates, but travels bodily so that this packing pad 6 remains horizontal, but will move in a counter-clockwise direction as viewed in Fig. 1, and will, therefore, come down into the can, move along with the can for a short distance, and then rise 110

away from the can. This packing device is similar to that shown in the patent to Fluck No. 1,307,248, granted June 17, 1919. In this prior patent, a plurality of packing pads are shown and described, while in the drawings, only one is shown. The detail structure for supporting and operating this packing device as shown in the drawings, forms the subject-matter of a pending application of George Fluck, Serial No. 45,986, filed July 24, 1925. The present invention has to do entirely with the construction of the packing device and not to the manner of mounting and operating the same. The packing device 6 consists of a disk-shaped body portion, on the under face of which is mounted a cutting disk 8. This cutting disk 8 has a depending flange 9, the inner edge 10 of which is a sharp cutting edge. Attached to the under face of this cutting disk is a pad 11. A bolt 12 secures the pad and disk to the packing device 6. This securing means may be of any desired construction. The pad 11 has an annular recess 13 therein, and a series of perforations 14 which lead from the face of the pad into the recess. When this packing device comes down on to the cam C, the pad will move into the can body, while the cutter will move down outside of the can body close to the flange at the upper end of the can body. Any floating content in the can body will be engaged by the cutting edge 10 of the cutting device, and severed. This releases the floating content so that the pad 11 will readily force the same down into the liquid content of the can. It is very desirable in some instances, such as packing string beans, to depress the floating content without overflowing the can. In the present construction, the perforations 14 serve as a means for permitting the brine or liquid content of the can body to pass up into the recess 13. Thus it is that the packing pad may move down into the can body without causing any overflowing of the same. When the pad is raised from the can body, the brine or liquid content in the recess 13 will quickly drain back into the can body. It will be understood, of course, that the pad 11 does not make an air-tight contact with the under face of the disk 8, and therefore, the air may escape from the recess 13 permitting the brine to flow into the same.

From the above it will be apparent that I have provided a packing device which insures that the floating content will be depressed into the can body and drawn off from the flange so that the flange is freed from any content all the way around. Furthermore, it insures that the floating content may be depressed without causing any

undue overflowing of the liquid content of the can body.

It is obvious that minor changes in the details of construction and the arrangement of the parts may be made without departing from the spirit of the invention as set forth in the appended claims.

Having thus described the invention, what I claim as new and desire to secure by Letters-Patent, is—

1. A packing device for closing machines comprising a packing pad adapted to be moved into the can body for depressing the floating content thereof, and a cutter surrounding and spaced from said packing pad adapted to move down over the can body and cut off any content of the can body overlying the flange of the can body. 80

2. A packing device for closing machines comprising a cutting disk having a depending flange with a cutting edge at the inner side thereof adapted to move down along the flange of the can body for cutting off any overlying content in the can, said packing device having a packing pad located within the cutting edge of said disk and spaced therefrom and adapted to move down into the can body for depressing the floating content. 85

3. A packing device for closing machines comprising a packing pad adapted to be moved into the can body for depressing the floating content thereof, and a cutter surrounding and spaced from said packing pad adapted to move down over the can body and cut off any content of the can body overlying the flange of the can body, said pad having a recess therein, and openings leading from the lower face of said pad into said recess, whereby the liquid in the can may pass out into said recess when the pad moves into the can body, and may be drawn back into the can when the pad is raised. 95

4. A packing device for closing machines comprising a cutting disk having a depending flange with a cutting edge at the inner side thereof adapted to move down along the flange of the can body for cutting off any overlying content in the can, said packing device having a packing pad located within the cutting edge of said disk and spaced therefrom and adapted to move down into the can body for depressing the floating content, said pad having a recess therein, and openings leading from the lower face of said pad into said recess, whereby the liquid in the can may pass out into said recess when the pad moves into the can body, and may be drawn back into the can when the pad is raised. 110

In testimony whereof, I affix my signature.
HENRY A. FINK.
